UNITED STATES PATENT OFFICE

GUSTAV DITTMAR, OF ST. LOUIS, MISSOURI, ASSIGNOR OF ONE-HALF TO ARTHUR O. WILKENING, OF ST. LOUIS, MISSOURI

CHAIR

Application filed August 9, 1930. Serial No. 474,167.

My invention relates to chairs, and, more particularly to porch and lawn chairs.

The object of my invention is to provide a chair wherein the chair back, seat and the arm rests thereof may be readily adjusted to several desired angles with respect to the frame thereof.

A further object of the invention is the provision of a foot actuated lever, which 10 when depressed at its rearmost end, will tend to elevate the back of the chair sufficiently to remove an element thereof from receiving recesses therefor to permit changing the inclination of the chair back.

15 A further object of the invention is the provision of slidable connections between the chair back and the arm rests of the chair so that the arm rests will change the angle of their position with that of the chair back.

20 When moved from one position to another.

A still further object of the invention is the provision of an adjustable chair which 25 possesses advantages in points of simplicity and efficiency, and, at the same time proves itself comparatively inexpensive in cost of manufacture.

With the above and other objects in view, the invention consists in the novel features of 30 construction, arrangement and combination of parts hereinafter more fully described and finally pointed out in the claims hereto appended.

35 Referring to the accompanying drawings forming a part of this specification, wherein like characters of reference denote similar parts throughout the several views:

Fig. 1 is a vertical sectional view of a 40 chair embodying the features of my invention.

Fig. 2 is a view showing the arm rests in cross section and the means for slidably supporting the rear ends thereof.

45 Fig. 3 is a lower plan view of the rear portion of one of the arm rests.

Fig. 4 is a front elevation of the chair.

Fig. 5 is a sectional elevation taken on line 5—5 of Fig. 1.

50 Fig. 6 is a detail showing the connection

between one of the ends of one of the chair back cleats and one of the arm rests.

In the drawings I have shown the chair as embodying a frame comprising a pair of suitable vertical front legs 1, a pair of suitable side leg members 2, the upper and lower front cross rails 3 and 4, respectively, the rear cross rail 5 and a pair of side rack members 6.

The side leg members 2 are suitably fixed 60 at their forward ends to the front legs 1. The side members 2 are directed downwardly and rearwardly from the front legs 1 and are each provided at their rear ends with a lower flat face 7 to act as a rear foot for each side leg 2 of the chair. The front cross rails 3 and 4 are suitably connected at their ends to the front legs 1 and the rear cross rail 5 is suitably connected to the side leg members 2, as will be apparent from Figure 1.

In carrying out the aim of my invention, I employ a suitable chair seat designated generally as A and embodying a pair of side cleats 8 upon which are secured a plurality of cross seat boards 9. The seat cleats 8 are also provided with a rear cross cleat member 10 having an inclined forward face 11. The cleat 10 is spaced from the rearmost seat board 9 so as to provide a transverse slotted passage 12 through which a chair back designated generally as B passes, as shown in Figure 1. The chair seat A is hingedly connected at its forward corners by means of suitable hinge members 13 secured to each of the seat cleats 8 and the upper front cross rail 3.

The chair back B embodies a plurality of suitable boards 14, which boards are united in suitable spaced relation by means of the cleat members 15, 16, 17 and 18. The chair back cleats 16, 17 and 18 extend beyond the side edges of the chair back, as will be apparent from Fig. 4, the purpose of which will be apparent hereinafter.

The chair frame is provided with a pair 95 of suitable arm rests 19 which are pivotally connected, as at 20, near their forward edge to the upper ends of the front legs 1.

The rear end portions of the arm rests 19 are remounted upon the extending ends 21 of the

chair back cleat 16 which supports the rear ends of the hinged arm rests 19. The under face of each arm rest 19, at the rear end thereof, is provided with a longitudinal recess 22 adapted to receive the head 23 of a screw, or its equivalent 24 carried by each extended end 21 of the chair back cleat 16 and each screw 24 is guided by means of a slotted metallic guide member 25 which has its forward end 5 open and its rear end closed, as will be apparent from Fig. 3. This arrangement permits the arms to slide upon the ends 21 of the cleat 16 and also prevents the arm rests 19 from being accidentally lifted upwardly and 10 disconnected from their supporting ends 21 of the cleat.

The rear ends of the seat cleats 8 are adapted to rest upon the extended ends 26 of the cleat 17 of the chair back B which act as a 20 support therefor and the extremities of this cleat stop short of the inner faces of the side leg members 2, as shown in Fig. 4.

The ends 27 of the chair back cleat 18 are adapted to seat themselves in recesses 28, 29 25 or 30 of the side racks 6, which racks act as supports for the chair back and limit downward movement of the chair back B.

A suitable foot actuated lever 31 is pivoted below the rear cross cleat 5 by means of the 30 pin connection 32 supported by a suitable strap member 33 carried by the rear cross cleat 5. The foot actuated lever is provided with a suitable foot plate 34 at its rear end, which is adapted to be engaged by means of 35 the foot of the operator when it is desired to change the inclination of the chair back B. The foot lever 31 extends forwardly from the rear cross cleat 5 and passes through a slotted passage 35 at the lower end of the 40 chair back and the lower end of the passage is closed by means of a suitable strap member 36 which limits downward movement of the forward or long end of the foot lever 31.

A pair of stop cleats 37 are secured to the 45 inner faces of the side racks 6 to limit extreme upward movement of the chair back B when lifting the cleat 18 from the recesses of the side racks for changing the inclination of the chair back.

To change the inclination of the chair back which simultaneously changes the angle or 50 position of the chair seat and the arm rests therewith, the operator presses down upon the lever plate 34, which causes the upper edge of the forward end portion of the lever 31 to engage the lower edge 38 of the cleat 18 of the chair back, thereby raising the supporting ends 27 of the chair back cleat 18 upwardly out of the side rack recesses, in 55 which ever pair of rack recesses they may be seated, and when this has been done, the operator by grasping the upper end of the chair back may move, or swing the chair back to the desired inclination and then allow the 60 ends 27 of the cleat 18 to drop into the desired 65 ends 27 of the cleat 18 to drop into the desired

recesses of the side racks 6. While I have shown the chair back B in full lines in its forwardmost position, and in dotted lines in two additional positions, it is evident that the number of positions the chair back can be moved into will depend upon the number of recesses carried by the side racks 6. In adjusting the chair back, it will be observed that the chair seat and the arm rests always change their positions therewith.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. In a chair construction, a frame having a pair of its side members provided with a plurality of recesses, a seat having a slotted opening hinged at its forward end to the frame, a chair back passing through the slotted opening of the seat, a transverse cleat on the back the ends of which support the rear end portion of the seat, a second transverse cleat on the chair back disposed below the first mentioned cleat and having its ends seated in a pair of the frame recesses, a pair of arm rests hingedly connected at their forward ends to the frame, a third transverse cleat on the chair back disposed above the first mentioned cleat and having its ends supporting the rear ends of the arm rests and a sliding connection between the ends of said third mentioned cleat and the rear ends of the arm rests.

2. In a chair construction, a frame having a pair of its side members provided with a plurality of recesses, a seat having a slotted opening hinged at its forward end to the frame, a chair back passing through the slotted opening of the seat, a transverse cleat on the back the ends of which support the rear end portion of the seat, a second transverse cleat on the chair back disposed below the first mentioned cleat and having its ends seated in a pair of the frame recesses, a pair of arm rests hingedly connected at their forward ends to the frame, a third transverse cleat on the chair back disposed above the first mentioned cleat and having its ends supporting the rear ends of the arm rests, a sliding connection between the ends of said third mentioned cleat and the rear ends of the arm rests and a foot actuated lever pivoted to the frame and disposed below the chair back

adapted when depressed at its rear end to elevate the chair back for elevating the lowermost chair back cleat from engagement with the frame recesses to permit moving of the chair back from one position to another.

5 3. An adjustable chair comprising a frame, a seat, a chair back and a pair of arm rests, said seat being hinged at its forward end to the frame and supported at its rear end by the back, said arm rests being pivotally connected at their forward ends to the frame and having slidable connection at their rear ends with the back, means carried at the lower end of the back and engageable in recesses upon opposite sides of the frame below the seat for holding the back in any one of its adjusted positions.

4. An adjustable chair comprising a frame, a seat, a chair back and a pair of arm rests, said seat being hinged at its forward end to the frame and supported at its rear end by the back, said arm rests being pivotally connected at their forward ends to the frame and having slidable connection at their rear ends with the back, means carried at the lower end of the back and engageable in recesses upon opposite sides of the frame below the seat for holding the back in any one of its adjusted positions and foot actuated means

25 30 for disengaging the means carried by the back from the frame recesses prior to changing the position of the chair back which simultaneously changes therewith the position of the seat and the arm rests relative

35 to the frame.

5. An adjustable chair comprising a frame, a seat, a chair back and a pair of arm rests, said seat being hinged at its forward end to the frame and supported at its rear end by the back, said arm rests being pivotally connected at their forward ends to the frame and having slidable connection at their rear ends with the back, means carried at the lower end of the back and engageable in recesses

40 45 upon opposite sides of the frame below the seat for holding the back in any one of its adjusted positions, foot actuated means for disengaging the means carried by the back from the frame recesses prior to changing

50 55 the position of the chair back which simultaneously changes therewith the position of the seat and the arm rests relative to the frame and means carried by the frame adapted to limit upward movement of the chair back when making adjustments thereof.

6. A chair comprising a frame including vertical front legs, a pair of inclined side leg members, front cross rails and a rear cross rail, a seat hingedly connected at its front end to one of the front cross rails, a pair of side racks having upper facial recesses connecting the lowermost of the front cross rails with the rear cross rail, a movable chair back, a cross cleat carried by the chair back, the ends of which support the rear end of the

seat, a pair of arm rests pivoted at their front ends to the front legs, a cross cleat carried by the chair back, the ends of which support the rear ends of the arm rests, means for slidably connecting the rear ends of the arm rests with the ends of said cleat, a cross cleat carried near the lower end of the chair back, the ends of which are seated in the recesses of the side racks, a foot actuated lever pivoted to the frame and disposed below the chair back for raising the latter cleat from the side rack recesses prior to adjusting the chair back from one position to another and means for limiting upward movement of the chair back while making adjustments thereof.

In testimony whereof, I have hereunto affixed my signature.

GUSTAV DITTMAR.
